FRANK M. LEAVITT, OF SMITHTOWN, NEW YORK, ASSIGNOR TO E. W. BLISS COMPANY,
OF BROOKLYN, NEW YORK, A CORPORATION OF WEST VIRGINIA.

GYROSCOPE-SPINNING MECHANISM.

1,185,210.

Specification of Letters Patent.

Patented May 30, 1916.

Application filed March 14, 1912. Serial No. 683,899.

To all whom it may concern:

Be it known that I, FRANK M. LEAVITT, a citizen of the United States, residing at Smithtown, in the county of Suffolk and 5 State of New York, have invented certain new and useful Improvements in Gyroscope-Spinning Mechanism, of which the following is a specification.

This invention relates to mechanism for 10 spinning and unlocking a gyroscope such as is used for controlling the steering of automobile torpedoes. Such gyroscope comprises a fly-wheel mounted in gimbal rings so as to be capable of universal motion, with 15 means for locking it so as to confine the fly-wheel to a fixed axis during spinning, means for then spinning it up to the required high velocity, and means for then unlocking the gyroscope to set it free, in order that as 20 its support (*i. e.* the torpedo hull) changes its position, the fly-wheel by virtue of its property of retaining fixity of axial direction may, by taking advantage of the differential motion between itself and its support, 25 be utilized to control the steering mechanism, whereby the torpedo whenever it diverts from its prescribed course may be steered back into such course. Although the steering of an automobile torpedo is the 30 principal practical use of such gyroscopic apparatus, yet the mechanism provided by the present invention is not necessarily limited to this utilization, although peculiarly adapted to the requirements thereof. 35 Gyroscopic fly-wheels have been spun up by a spring clock-work mechanism; or by blowing compressed air against the fly-wheel itself, the latter being formed with peripheral notches to constitute it a sort of 40 turbine; or by gearing the fly-wheel spindle to the propeller shaft or other rapidly revolving shaft and slipping the gearing after a sufficient interval to insure that the fly-wheel shall have been spun to the required 45 speed. The present invention utilizes compressed air (or equivalent fluid under pressure) for the purpose, but instead of having this act directly upon the fly-wheel, a special turbine is provided which is geared 50 to the fly-wheel and after a predetermined interval sufficient to insure the proper spinning, the gearing is slipped or unmeshed and the air supply simultaneously shut off. At the same instant the gyroscope is un- 55 locked.

The accompanying drawings show the preferred embodiment of my invention as applied to the spinning up of a gyroscope suited for use in an automobile torpedo.

Figure 1 is a vertical longitudinal section 60 of the gyroscope mechanism, partly in elevation, showing the gyroscope locked and ready for the spinning operation; Fig. 2 is a similar view showing the parts after the unlocking operation; Fig. 3 is a view looking 65 toward the left end of the preceding figures, showing the turbine wheel in elevation, its nozzle in section, and the connection with the air control valve; Fig. 4 is a section looking in the same direction as 70 Fig. 3 and cut in the plane of the line 4-4 in Fig. 1. Fig. 5 is a plan partly in horizontal section.

Referring to the drawings, A designates the fly-wheel of the gyroscope, *a* being its 75 spindle and *b* its gimbal rings, the outer ring being hung as usual in a support *d* which is fixedly mounted in the hull of the torpedo. The spindle *a* carries a gear wheel *e* which may mesh with a gear *f* which is carried 80 upon one end of a shaft *g* on the opposite end of which is carried the turbine *B*. The shaft *g* has bearings in a slide *C*, preferably constructed as a tubular sleeve, which may slide endwise in frames *h* and *i*. The sleeve 85 *C* in one extreme position, shown in Fig. 1, brings the gear *f* into mesh with the gear *e*, and at the same time brings the turbine wheel *B* into the plane of a turbine nozzle *D*. In the other extreme position shown in 90 Fig. 2, the gear *f* is out of mesh with the gear *e* and the turbine *B* is carried out of the plane of the nozzle *D*.

A locking pin *E* is mounted in the line of the axis of the fly wheel, and in the position 95 shown in Fig. 1 its end enters a socket *j* in the inner gimbal ring *b* and locks the gimbals fast in the position required for spinning up the fly wheel. At the end of the spinning operation the locking pin is 100 withdrawn to the position shown in Fig. 2; for this purpose it is made to slide in suitable bearings in the frames *h* and *i*, and is connected to the slide *C* as by means of a fork *k* projecting down from the slide and 105 engaging between opposite shoulders on the locking pin.

The slide *C* is acted upon by a spring to give it a strong tendency to move to the position shown in Fig. 2. This spring might 110

- be variously applied, the arrangement shown being that a forked lever F engages a projection on the slide and has an elbow arm which receives the pull of a spring S.
- 5 In the locked position shown in Fig. 1, the slide C is locked in place by any suitable latching means, preferably a sliding latch G (Fig. 4) which enters a locking notch g' in the side of the slide. A spring l presses the latch into place. At the termination of the prescribed period of time required for spinning up the fly wheel, the latch G is forced back to free the slide C, which thereupon is thrown over by the stress of the spring S to the position shown in Fig. 2.
- 10 The duration of the spin may be determined by any suitable sort of timing mechanism. One example of this is shown in Fig. 4. The shaft g carries a worm m (Fig. 20 1) which drives a train of gears comprising a worm wheel n and pinions o, o', p , the latter meshing with a rack q on a slide H. This slide is pressed by a spring H' against a stop shoulder h' which determines the 25 starting point of its travel. When the mechanism is started, the movement of the train causes a slow travel of the slide H in the direction of the arrow, which finally brings this slide into contact with a shoulder i' on the latch G, whereupon it carries the latch G with it until this latch is withdrawn from the notch g' and unlocks the slide C, whereupon this slide moves over quickly to the position shown in Fig. 2.
- 30 35 The train is shown as mounted in a frame r which is supported on the slide C, so that this train moves with the slide. The movement of the slide C not only displaces the turbine B but also shuts off air (as will be described) and the turbine soon comes to rest so that its screw m ceases to further drive the train. The duration of the spin is determined by the speed of the turbine shaft g , the proportions of the gearing, and the 40 45 distance separating the slide H from the shoulder or abutment which it strikes on the latch G. The width of this space may be made variable at will in case it is desired to be able to control the duration of the spin. For this purpose an adjusting screw s (Fig. 4) may be provided for varying the starting point from which the slide H travels, and thus varying the duration of its travel.
- 50 55 The compressed air for spinning the turbine is admitted from any source of air pressure through a pipe t controlled by a starting valve I. The air pipe then leads to a shut-off valve J from which a duct t' leads to the nozzle D. The valve J has a stem J' which projects down through it and is acted upon by an arm F' projecting from the spindle of the lever F.
- 60 65 The spinning mechanism is started in operation by the opening of the starting valve

I which admits compressed air to the turbine. This valve is here shown in a merely diagrammatic manner. In a torpedo, the ordinary starting valve which admits compressed air from the reservoir to start the 70 engine, may be utilized for admitting air to the spinning mechanism, and will constitute the equivalent of the valve I herewith indicated. The valve J is normally open so that the air has free access to the turbine. 75 The air blowing through the nozzle starts the turbine B which revolves with accelerating speed, and its motion is communicated through the gears $f e$ to the fly-wheel. This motion also drives the timing mechanism, 80 and at the end of the prescribed movement the latch G is withdrawn and the slide C flies over as described. The accompanying movement of the lever F carries its arm F' which no longer holds up the valve stem J' , 85 and the valve J thereupon instantly closes, shutting off the air from the turbine and preventing waste of air. The gyroscope fly-wheel having been spun up to the requisite speed before this unlocking movement, 90 is unlocked by the retraction of the locking pin E. In a torpedo, all this occurs while the torpedo is moving through the launching tube and before it so far emerges therefrom as to lose its fixed direction as determined by the aiming of the tube.

The mechanism thus described is simple and compact, is very certain in its operation, and requires only to be driven by a suitable air pressure (which in a torpedo is 100 assured) to cause the spinning of the fly-wheel to the requisite high velocity, and to cause the unlocking movement to be effected within the very brief time limited by the movement of the torpedo within its launching tube.

To set the apparatus before launching, it is only necessary to move the parts to the position shown in Fig. 1, whereupon the latch G is pressed by its spring l into engagement with the locking notch g' , thereby securely locking the slide C. This movement protrudes the locking pin E to lock the gimbal ring. Of course the gimbals must first have been restored to normal position so as to bring the socket j into line with the locking pin.

The present invention is not confined to the construction or arrangement of mechanism shown, but this may be varied within 120 considerable limits, as will be apparent to any skilled mechanician, and as may be required according to any special purpose for which the mechanism is to be adapted.

The means for spinning a gyroscope fly-wheel introduced by the present invention has the advantage that it spins the fly-wheel almost instantaneously and while the torpedo is still moving within the launching tube, and hence before it can possibly de- 130

viate from its original direction or aim; and of insuring that the fly-wheel shall continue spinning for the longest possible time, this being a condition of the utmost importance to meet the requirements of the present long range torpedoes. As compared with the old spring or clock-work spinning means, it has the advantage of a far more forceful spin of the wheel, and it avoids any risk of failure due to the breaking of a spring or the derangement of the complicated clock-work mechanism. The early attempts to utilize an air jet for spinning the fly-wheel by directing the jet against teeth formed on the surface of the wheel, had the disadvantage that these teeth acted as fans to churn the surrounding air into eddy currents, thereby retarding the wheel and causing it to run down so quickly as to be useless for the present long range torpedoes. The spinning of the fly-wheel by gearing it to the turbine shaft, has the disadvantage that the gyroscope cannot be spun until the starting of the engine; whereas it is desirable that the engine be not started until after the torpedo has left the launching tube, and hence not until after the spinning of the gyroscope has been completed. The present invention obviates these several disadvantages.

What I claim is:

1. The combination with a gyroscope of a shaft geared to the flywheel thereof, a turbine on said shaft, a slide carrying said shaft, a timing device, and means controlled thereby for displacing said slide at the end of the spinning operation.
2. The combination with a gyroscope of a lock for the gimbal thereof, a shaft geared to the flywheel thereof, a turbine on said shaft, a slide carrying said shaft, and means for displacing said slide and withdrawing said lock at the termination of the spinning.
3. The combination with a gyroscope of a lock for the gimbal thereof, a turbine, a shaft and gears connecting said turbine to the fly-wheel, a slide connected to said lock and to one of said gears, and means for dis-

placing said slide at the end of the spinning operation to unmesh said gears and unlock the gyroscope.

4. The combination with a gyroscope of a lock for the gimbal thereof, the flywheel thereof having a gear, a turbine, a shaft carrying said turbine and having a gear engaging said gear on the flywheel, a sliding sleeve inclosing said shaft, a worm on said shaft, a timing device driven by said worm, and means released by said timing device for displacing said sleeve to unmesh said gear for unlocking the gyroscope.

5. The combination with a gyroscope of a lock for the gimbal thereof, a shaft geared to the flywheel thereof, a turbine on said shaft, a slide engaging said shaft, a latch for holding said slide in position, a spring tending to displace said slide, and means for withdrawing said latch at the end of the spinning operation.

6. The combination with a gyroscope of a locking pin for the gimbal thereof movable in line with the axis of the fly-wheel, a shaft geared to the fly-wheel, a turbine on said shaft, a movable part adapted to displace said shaft endwise, a latch for holding said parts in the locked position, a spring for retracting them when unlocked, and means for withdrawing said latch at the end of the spinning operation.

7. The combination with a gyroscope of a lock for the gimbal thereof, a shaft geared to the fly-wheel thereof, a turbine on said shaft, a train driven from said shaft, a latch for holding said shaft and lock in the locked position, means operated by said train for withdrawing the latch after the prescribed spin, and a spring for displacing said shaft and withdrawing said lock upon the release of said latch.

In witness whereof, I have hereunto signed my name in the presence of two subscribing witnesses.

FRANK M. LEAVITT.
